ELIAS H. KELLEY, OF NEW YORK, N. Y.

FRAUD-PREVENTIVE DEVICE FOR VENDING-MACHINES.

1,204,452.

Specification of Letters Patent. Patented Nov. 14, 1916.

Original application filed December 17, 1909, Serial No. 533,638. Divided and this application filed October 27, 1910. Serial No. 589,301.

To all whom it may concern:

Be it known that I, ELIAS H. KELLEY, a citizen of the United States, residing in the borough of Manhattan, city, county, and 5 State of New York, have invented a new and useful Improvement in Fraud - Preventive Devices for Vending-Machines, of which the following is a description.

This invention has reference to vending 10 machines of the coin-controlled type, and particularly relates to fraud preventive mechanism for vending machines of any type.

Among the objects of my invention may 15 be noted the following: to provide means by which the machine is prevented from being tripped into action when the coin is not of the proper thickness; to provide means by which the check, intended to operate the 20 machine, can be accurately gaged as a preliminary to the operation of the machine; to provide a device for preventing the coin or check from tilting and, in combination with the gaging device, to aid the latter to perform 25 its functions; to provide a vending apparatus making it impossible for the machine to effect the delivery of an article with anything other than a good coin of proper thickness, or a check of predetermined character; to provide an apparatus with means which will enable the detection of slugs, spurious coins, disks, rings and other things in form similar to a coin.

With the above objects in view and others 35 which will be detailed during the course of this description, my invention consists in the elements, mechanisms, parts and features, and combinations of elements and mechanisms all as hereinafter described and claimed.

In order that my invention may be clearly understood, I have provided drawings wherein:

Figure 1 is an enlarged detailed view in longitudinal vertical section of so much of my coin-controlled apparatus as is deemed necessary to illustrate my present invention; Fig. 2 is a plan view of one of the slide mechanisms showing my fraud preventing device in its operative relation to the coin-detecting mechanism of the apparatus, parts being broken away and other parts being in section owing to the character of the figure; Fig. 3 is an end elevation and partial section taken substantially on the line 3—3 of

Fig. 1, the supporting plate, however, being omitted from this figure, and the arrow indicating the direction of sight; Fig. 4 is a perspective view of one of the coin-slides; and Fig. 5 is a perspective view of the bottom of the leveling-plate.

Referring to the drawings, the numeral 1 indicates the front-plate of the machine, 2 the supporting-plate, 3 the slide-plate, 4 the coin-slide provided at the front end with a 65 knob 5 by which the same may be manually operated. The coin-slide operates beneath the lower edge of the front-plate and, as shown in Figs. 2 and 3, the slide-plate, in which the coin-slide operates, supports a 70 standard 6 in connection with which operates a coin-ram, the parts of which are generally indicated by 7, this mechanism forming no part of my present invention but being claimed in my copending application No. 75 619,989, filed April 10, 1911, and being the same as that disclosed in my application Serial No. 533,638, filed December 17, 1909, of which this application and my application No. 619,989 are divisions. The juxtaposition of parts of my present invention with reference to the ram and the tripping-device, generally indicated by 8, is, however, a part 80 of my present invention. A coin-slide retrieving and locking mechanism, generally indicated by 9, is also shown in the drawings but forms no part of my present invention in the matter of its details and is shown in the drawings only to disclose an operative mechanism and identify the machine with that of my aforesaid parent application. Also a slide locking mechanism generally indicated by 10 is shown in the drawings but forms no part of my present invention.

The details of the coin-slide are shown in Fig. 4, and the operative relation of the same and the features thereof are shown in Figs. 1 and 3, in which latter the coin-slide 4, when in normal or inoperative position, extends 100 from the front edge of the slide-plate 3 to a point a short distance beyond the coin-escape aperture 11 of the slide-plate, as clearly shown in Fig. 1, a chute 12 coöperating with said aperture. The said coin-slide is provided with three parallel grooves 13, 14 and 15, Fig. 4, divided substantially centrally by a coin-receiving aperture 16. The central groove 14 extends from a point a short distance from the front end of said slide to 105

near its rear end. The groove 13 extends from the rear end of the slide to within a short distance of the front end of the groove 14. The groove 15 extends from the same point at the front end of the slide as the groove 13, to the rear end of the slide, which, at this side, is cut out to provide the angular recess 17. The slide on its left side, at its rear end beside the groove 15, is provided with a lug 18, having its front face inclined, as at 19, to form a cam-surface. The rear end of the slide, on its right side beside the groove 13, is provided with a V-shaped transverse notch 20 having no reference to my present invention. The diameter of the coin-receiving aperture 11 will be just sufficient to admit the coin for which it is intended. The coin-slide 4 is dove-tailed into the slide-holder 3 and is moved forward in said holder manually by the knob 5, screwed into an aperture at the front end of the slide, as at 21. The return movement is caused by retrieving mechanism 9.

A device for preventing the coin from tilting in the coin-slide and carried by the slide-plate 3 operates in conjunction with the coin-slide just described. It consists of a plate 22, Figs. 1, 3 and 5, having opposite lateral extensions 23 at rest on opposite sides of and secured to the slide-plate, by means of screws 24, passing through said plate 22 into the said slide-plate, said plate 22 being provided centrally with a longitudinal slot, 25 and, on opposite sides of said slot 25 with longitudinal depending ribs 26 and 27, which enter, respectively, the grooves 13 and 15 of the coin-slide and have their forward ends upwardly curved at 28 so as to freely admit the edge of the coin thereunder. The slot 25 registers with the central groove 14 of the coin-slide. The location of this plate 22 is in rear of the coin-receiving aperture 16 and a short distance in rear of the face-plate 1 of the frame. It extends rearwardly substantially to the coin-escape aperture 11, Fig. 1, and the ribs 26 and 27 extend to substantially the bottom of the grooves 13 and 15, which latter are in depth sufficient to have their bottom surface substantially flush with the surface of a coin inserted in the coin-aperture 16, the thickness of said slide below the bottom of said grooves being substantially that of the coin. Thus, with the coin in place in the coin-slide, it will be prevented from being tilted relatively to the slide, as the latter is moved forward, since the edge of the coin will slide freely under the ribs of the plate and will be properly presented to a coin-gage and detector which will be presently described. This anti coin-tilting plate is an important feature of my invention since, by preventing the coin from tilting in the coin-aperture 16, said coin will be properly passed forward to undergo certain tests described, and said plate 22 acts

positively to depress, if necessary, the coin in its slide and hold it therein.

As a preliminary detector, I have provided a thick-coin detector, or means for preventing a coin, having a greater thickness than the proper thickness of a good coin, from being pushed into the machine by the slide. This means consists of a depending finger 28 fixed by means of the screw 29, in the lug 30, projecting rearwardly from the inside of the face-plate 1 of the frame, the said finger extending into the central groove 14 of the coin-slide the proper distance and operating to hinder the passage of a coin which is too thick. The holding-screw 29 also permits vertical adjustment of said finger to a nicely so as to enable its lower end to be set just right for the accurate performance of its functions as described. The proper and accurate adjustment of the finger is aided by beveling the functional end thereof as indicated by 31, viz., rearwardly and upwardly; that is to say, with a front edge only in co-operative relation to the groove 14 of the coin-slide the position of the finger can be set without fear of any portion in rear of said edge interfering with the coin.

Should the thickness of the coin inserted in the coin-aperture 16 be less than that of a good coin, thus enabling the coin to pass the finger 28, I have provided gaging means controlled by the coin and operating upon the slide to prevent the latter from being pushed in to operate the machine. This thin-coin detector consists of the anti-friction roll 32 having its journal 33 extending through its carrier 34 and into the side-bars 35 of a frame or truck, the front ends of which side-bars extend between lugs 36 fixed to the opposite sides of the slide-plate 3 and journaled in said lugs by means of the pin 37, on which is also journaled the rear end of the carrier 34.

The rear or cross-bar 38 of the truck has extending from it a pin 39, which is screwed thereinto and which pin carries a stop-device 40, having a laterally extending portion 41, through which extends vertically a stop-pin 42, the lower end of which is beveled rearwardly and upwardly and which pin may be adjusted vertically by threading the same into the portion 41, as clearly indicated in Fig. 1. The stop-device 40 is adjustable on the pin 39, both circumferentially and longitudinally, by means of the screw 43, passing through said device and engaging said pin. The laterally-extending portion 41 disposes its pin 42 with its lower beveled end, directly in line with the lug 18 on the rear end of the coin-slide 4, so that, if a coin placed in the coin-slide be thinner than a good coin, and should pass the thick-coin finger 28 and thus pass under the roll 32, the latter will not be lifted, or not sufficiently lifted, and, conse-

quently, the truck will not be lifted, thus leaving the pin 42, with its beveled end, directly in the path of the lug 18, which will completely stop the progress of the coin-slide rearwardly. If, however, the coin placed in the coin-slide be of the same thickness as a good coin, it will pass the finger 28, the plate 22 and the roll 32 and lift the latter together with its truck and thus lift the stop-device, which will carry its stop-pin 42 out of the path of the cam-lug 18, on the coin-slide, and thus allow the coin to reach a position above the coin-escape aperture 11 preparatory to being passed therethrough into the chute 12, lying directly beneath the same. By beveling the pin 42, as shown, the return of the slide to normal position is permitted without hindrance from said pin, since the cam-face 19 of the lug 18 and the beveled end of the pin 42 will coöperate to lift the truck and stop-device.

The standard 6 is secured to the slide-plate 3 and is bored to receive the ram parts 25 7. The standard 6 is recessed at 44 to receive and permit movement of the rear end of the carrier 34. The standard 6 also carries a rearwardly extending lug 45, recessed to receive the upper end of a coiled-spring 30 46, the lower end of which engages the rear bar of the truck 35 and encircles a pin thereon and thus normally keeps the truck depressed with its stop-device in position such that the pin 42 of the latter will either 35 stop or permit the passage of the coin-slide, as previously indicated. The spring 46 is light and aids gravity in one direction, but does not materially impede the raising of the truck. The periphery of the roller 32 40 is rounded or U-shaped, as shown in Fig. 1, or may be flat as shown in Fig. 3, these shapes given to the periphery of the roller being in contradistinction to a V-shaped edge or periphery, since the function of the 45 roller is to feel and sensitively gage a coin as it passes thereunder and not to mark, score or impede the progress of the coin. For the same reason the spring 46 is made very light so as not to impose upon the 50 coin, through the roller, an excessive pressure. This is an important point, since the more sensitive the gage is the less impediment it will impose to the passage of the coin-slide, which, for this gaging operation, 55 should be permitted to move freely.

If the forward end of the coin-slide reaches the tripping-rod 47 of the tripping mechanism 8 the coin will have passed the magnet stop or lock 48, thick coin-detector 60 28, anti-coin tilting plate 22 and thin coin-detector 32, and will have reached the posi-

tion of the coin-escape aperture 11. In this position the coin undergoes a test for tensile strength imposed upon it by the ram-head 49 of the testing mechanism 7 working in the standard 6.

Having thus described my invention what I claim and desire to secure by Letters Patent is:

1. A coin-controlled apparatus for vending machines having, in combination, a reciprocatory slide; means coöperating with the slide, disposed in the path of movement of the coin contained therein, for engaging said coin, said means comprising a frame, a carrier and an anti-friction disk journaled in the carrier, the periphery of which disk is rounded so as not to impede the movement of the slide; means for supporting the carrier in the frame; and a journal-support for the frame and means for imposing a light pressure upon said disk. 70

2. In combination with the coin-slide of a vending machine, a plate arranged across the top of said slide, said slide having an aperture and being provided with parallel grooves extending in opposite directions from said aperture lengthwise of the slide; and said plate having ribs entering and operating in the grooves of the slide, whereby when the slide is moved the plate will 85 depress a coin placed in the aperture of the slide. 90

3. A coin-controlled mechanism for vending machines comprising a reciprocatory slide having an aperture for receiving a coin and provided longitudinally thereof with one or more grooves or slots; and a test-plate supported on opposite sides of the slide in a fixed position and having one or more ribs 100 coöperating with the slots or grooves of the slide, and arranged normally to enter said slots or grooves. 95

4. A coin-controlled mechanism for vending machines comprising a reciprocatory slide having an aperture for receiving a coin; a rectangular frame mounted above the slide and having testing means for coöperating with the slide, or a coin carried thereby; a test-plate arranged between the testing means and the slide, and having an aperture through which the testing means operates; the slide and test-plate being provided with one or more interacting ribs and slots extending longitudinally of the slide. 110 115

In testimony whereof I have hereunto signed my name in the presence of two subscribing witnesses.

ELIAS H. KELLEY.
